UNITED STATES PATENT OFFICE.

WALTER A. FRANTZ, OF CLEVELAND, OHIO, ASSIGNOR TO THE ARZA OIL PUMP COMPANY, OF CLEVELAND, OHIO, A CORPORATION OF OHIO.

PUMP.

Application filed April 2, 1924. Serial No. 703,706.

This invention relates to pumps and has especial reference to that type of pump employed in connection with lubricating oil barrels. The objects of the invention are the provision of a pump of particularly cheap and simple construction which can be applied interchangeably to barrels of all standard and customary sizes to withdraw oil therefrom; the provision of a simplified and improved pump mounting comprising a new arrangement of air vent, drip pan, and shelf; while further objects and advantages of the invention will become apparent as the description proceeds. The fundamental object of the invention is the provision of an oil pump of such cheap construction that it can be included in the sale of oil in barrel lots, without increasing the price to the customer, thereby stimulating the purchase of oil in this form, and reducing the price of oil to the individual users by dispensing with the necessity of purchasing it in small quantities as required.

In the drawings accompanying and forming a part of this application I have shown certain simple forms in which my inventive idea can be embodied although it will be understood that I do not limit myself to these details of construction.

Figure 1 is a side elevation of my complete pump in place in an oil barrel, the latter being shown in section; Figure 2 is a longitudinal sectional view through my improved pump; and Figure 3 is a horizontal sectional view upon the broken line 3—3 of Figure 1.

My improved pump comprises a pair of interfitting cylindrical metal pipes 1 and 2, the former constituting a cylinder or casting and the latter a plunger therefor. These pipes are preferably made of thin metal, such as steel or aluminum, and the size of the inner is such as to slide easily within the outer. Tightly secured in the lower end of the outer pipe is a suitable closure 3 having a central aperture 4 on which rests a valve 5 preferably consisting of a steel bearing-ball. This closure is held in place in any suitable manner, but preferably by bending in certain portions 6—6 of the pipe, leaving other portions 7—7 undeflected and thereby defining notches 8. Tightly secured in the lower end of the inner pipe is a similar closure 10 similarly formed with an aperture 11 on which is seated a similar ball

valve 12. The closure 10 is likewise secured in place by suitable crimping of the pipe thereto, and in this connection I have shown the exterior of the pipe 2 as slightly enlarged at this point to form a rim 13 fitting slidably within the pipe 1 and steady-
ing the same. There is no advantage in having the pipes fit snugly, but rather a disadvantage since accidental dents in the outer pipe are more injurious.

Secured to the upper end of the pipe 1 is a suitable packing gland 15 containing a mass of soft packing 16 which makes a tight seal with the pipe 2. If the wall of the pipe 1 is too thin to have this gland screwed directly thereon, a reinforcement 17 may be employed at this point. Tightly secured to the top of the pipe 2 is the discharge spout 18 which also preferably constitutes a handle for operating the pump. This part is preferably made of a casting of brass or aluminum and is tightly secured to the tube 2 by a threaded or pressed joint reinforced by suitable rivets 19. The end of this discharge spout is formed with a downturned discharge neck 20.

Surrounding the pipe 1 intermediate its ends is a sleeve 21 from one side of which projects a neck 22 terminating in a hollow drip pan 23. This sleeve is internally threaded at its upper and lower ends to receive respectively the clamping nut 24 and the attaching nipple 25. This clamping nut consists of a bushing formed externally with a slightly tapered thread adapted to screw into the sleeve 21, and internally with a plain cylindrical surface adapted to receive snugly the pipe 1, this bushing being split as shown at 26. The nipple 25 is an ordinary externally threaded plumber's nipple of suitable length screwed into the sleeve 21 and preferably fastened permanently by suitable means such as rivets 27, leaving its projecting end free to screw into an oil barrel. Internally this nipple is larger than the pipe so as to define therewith an annular passage 28. Between the nut 24 and nipple 25 the sleeve is formed with a channel 30 communicating with the passage 31 from the interior of the drip pan 23. This pan is also provided with suitable ledges 32—32 for the reception of a measuring can or device 33 of any suitable type.

In use the nipple 25 is screwed into the spigot hole 35 (or sometimes the bung hole 110

if more convenient) of an oil barrel 36, either with or without the use of of a bushing 37 depending upon the size of the hole. The shelf 23 can be used as a wrench for this purpose, but the nut 24 is meanwhile preferably loosened. The pipe 1 is now pressed down to the bottom of the barrel where the notch 8 insures ready ingress of oil, and the nut 24 is tightened. The plunger is easily reciprocated, the packing 16 preventing ingress of air on the upstroke or egress of oil upon the down stroke. No attempt is made to measure oil by the stroke, since most users prefer to use measuring vessels, than to trust the calibration of any pump. Entrance of air to the barrel is pemitted by the passage 28 which also returns any drip, although drip is largely prevented in case the operator gives the plunger a slight upward movement at the instant of leaving the device.

While I have described in considerable detail the preferred construction of my improved pump, I do not limit myself to these details except as specifically recited in my several claims, as many changes can be made within the scope of my invention.

Having thus described my invention what I claim is:

30 1. A barrel pump comprising, in combination, a pair of upright interfitting cylindrical pipes, one slidable within the other, inlet valves at the lower ends of said pipes, a combined handle and discharge spout at the upper end of the inner pipe, and a pack-

ing gland carried by the upper end of the outer pipe and slidably engaging the inner pipe in leak-preventing relation.

2. In a barrel pump, in combination, a pair of interfitting cylindrical pipes, one 40 constituting a cylinder and the other a plunger, a drip pan having a sleeve embracing said cylinder, said drip pan having a passageway communicating with an intermediate portion of said sleeve, an externally 45 threaded nipple surrounding and spaced from the cylinder and rigid with the lower part of said sleeve, said nipple adapted to be screwed into an oil barrel, and clamping means carried by said sleeve at a point above 50 said passageway and adapted to secure said cylinder tightly in said sleeve.

3. In a barrel pump, in combination, a pair of interfitting cylindrical pipes, one 55 constituting a cylinder and the other a 60 plunger, a drip pan having a sleeve embracing said cylinder, said drip pan being hollow and having a passageway communicating with an intermediate portion of said sleeve, a threaded nipple surrounding and 65 spaced from the cylinder and threaded into the lower part of said sleeve, said nipple adapted to be screwed into an oil barrel, and a clamping nut screwed into the upper end of said sleeve and adapted to secure said cylinder tightly thereto.

In testimony whereof, I hereunto affix my signature.

WALTER A. FRANTZ.
